UNITED STATES PATENT OFFICE

100,477

DESIGN FOR A TOY WAGON

Edgar G. Petersen, Chicago, Ill., assignor to Pines
Winterfront Co., Chicago, Ill., a corporation of
Illinois

Application April 3, 1936, Serial No. 61,930

Term of patent 3½ years

To all whom it may concern:

Be it known that I, Edgar G. Petersen, a citizen of the United States, residing at Chicago, county of Cook, and State of Illinois, have invented a new, original, and ornamental Design for a Toy Wagon, of which the following is a specification, reference being had to the accompanying drawing, forming a part thereof:

In the drawing,

Figure 1 is a perspective view of the toy wagon embodying my design;

Fig. 2 is a front elevational view of the same; and

Fig. 3 is a rear elevational view thereof.

The characteristic feature of my design resides in the rear end portion of the wagon, consisting of the box of the wagon sitting above the

shrouds, said box having sloping sides and rear, the top edge of the rear portion curving below the top edge of the front portion giving a streamline effect. The shroud between the mud guards slopes away from the body in easy curves and in all directions and dips at its tail portion in harmony with the dip of the top edge of the rear end of the box. The box and the rest of the body are distinctly separate, but are each curved so as to blend together and give a combined effect of strength and speed in an harmonious unit.

I claim:

The ornamental design for a toy wagon, as shown and described.

EDGAR G. PETERSEN.
